[57] CLAIM

The ornamental design for a toy sand wheel, as shown and described.

DESCRIPTION

FIG. 1 is a front elevational view of a toy sand wheel showing an embodiment of my new design and is also a mirror image of rear elevational view thereof;

FIG. 2 is a left side elevational view thereof and is also a mirror image of right side elevational view thereof;

FIG. 3 is a top plan view thereof; and,

FIG. 4 is a bottom plan view thereof.

The broken line showing of the bucket and sand toys in FIG. 1 is for illustrative purposes only and forms no part of the claimed design.
